UNITED STATES PATENT OFFICE.

ELMER C. NORTHRUP, OF SAN FRANCISCO, AND EDWARD H. SPECHT, OF OAKLAND,
CALIFORNIA.

APPARATUS FOR TREATING PACKAGED GOODS.

Application filed June 28, 1920. Serial No. 391,046.

To all whom it may concern:

Be it known that we, ELMER C. NORTHRUP and EDWARD H. SPECHT, citizens of the United States, and residents, respectively, of the city and county of San Francisco, and Oakland, county of Alameda, and State of California, have invented a new and useful Apparatus for Treating Packaged Goods, of which the following is a specification.

10 Our invention relates to means for treating, as by cooking, canned or other packaged material, and one of the objects of our invention is the provision of an apparatus of this character, in which each package is moved though a treating chamber while being repeatedly inverted or turned end for end, and also rotated about its axis or rolled, so that the contents of the package is stirred about.

20 Another object of the invention is to provide an apparatus having a rotatable carrier for the packages of material undergoing treatment, and in which no moving parts other than the carrier are required to cause 25 the progression of the packages through the apparatus; the structure of the carrier being such that rotary movement and the force of gravitation effect the desired progression of the package.

30 The invention possesses other objects and features of advantage, some of which, with the foregoing, will be set forth in the following description of the preferred form of our invention which is illustrated in the drawings accompanying and forming part of the specification. It is to be understood that we do not limit ourselves to the showing made by the said drawings and description, as we may adopt variations of the preferred form 35 within the scope of our invention as set forth in the claims.

Referring to the drawings:

Fig. 1 is a vertical sectional view through the cooker taken in the plane indicated by the line 1—1 of Fig. 2. Fig. 2 is an elevation of the discharge end of the cooker, portions being broken away better to disclose the structure. Fig. 3 is a detail showing a portion of the charging end of the carrier when made for hand feed. Fig. 4 is a vertical sectional view through a modified form of cooker. Fig. 5 is a vertical sectional view taken in planes indicated by line 5—5 of Fig. 4, and showing the cooker as arranged

for a shortened cooking period. Fig. 6 is a perspective of a portion of the modified cooker.

In terms of broad inclusion the structure of our invention comprises a runway, or for the sake of increased capacity, a plurality of runways; means for introducing packaged goods into the runways; means for applying to the goods in the runways the treatment desired, which in the instant case is the application of heat to cook the contents of the package; means for moving the runways to inverted position so as to invert the package and means fixed for movement with the runways for causing the packages to progress through the runways and be discharged therefrom.

Journalized in bearings 2 on the suitably formed frame 3 is a shaft 4 upon which a cylindrical carrier is fixed for rotation therewith. The carrier comprises a cylindrical frame in which spokes 6, radiating from spaced hubs 7, keyed to the shaft 4, are connected by cross bars 8, on which the rings 9 are secured. Connecting the rings and lying in planes parallel to the axis of the shaft, are channels 10. The channels are spaced circumferentially about the rings and are arranged in pairs, the channels of each pair lying parallel to and opening toward each other as shown in Fig. 2. Each pair of channels thus constitutes a runway through which the packages or cans 11 move while in the apparatus. The outer edges of the channels are surrounded by the rings 12 concentric with the rings 9 so that a rigid structure is provided. A large worm wheel 13 in mesh with the worm 14 driven by the belt 15 from any suitable source of power, provides means for revolving the carrier. The length of the carrier frame may be as desired, its length and speed of rotation, determining the length of the period of cooking or other treatment.

Surrounding the carrier is a housing 16 the interior of which is heated to the required temperature by any desired means. Preferably coils 17 are arranged between the carrier and the housing and are fed from the valve controlled supply main 18. Live steam is also admitted into the housing from coils 19 connected at one end into the supply main, by valve controlled pipe 20 and arranged across the lower portion of the hous-

ing. These coils 19 are provided with apertures so that jets of hot steam play upon the the cans in the runways as the carrier turns from the loading position. Owing to the 5 open nature of the carrier structure, the heat within the housing readily reaches all portions of the cans.

Means are provided, stationary on the carrier, for effecting the movement of the cans 10 11 through the runways when the carrier is revolved. On the inside of the flanges of the channels in each pair, a track for controlling the movement of the cans rolling thereon, is fixed. Each track comprises an 15 inclined portion 21, and a stop portion 22, and the outside pair of tracks are so arranged relative to the inside pair of tracks, that the stop portions of each pair of tracks are opposite the beginning of the inclined 20 portions of the other or companion pair of tracks. In other words, opposite sides of the runway are provided with pockets, the pockets on each side being staggered in respect of those on the opposite sides. The 25 first inclined portion of the outer pair of tracks is extended somewhat to form a loading lip 23 upon which the entering cans roll from appropriate loading or feeding means, or are placed by the operator. The loading 30 preferably occurs at the bottom of the turn of the carrier, and the can rolls down against the first stop. As the carrier revolves, the runway is slowly inverted, and the can falls from the outer tracks which 35 are then on the upper side of the runway to the beginning of the downwardly slanting portion of the inner tracks. It then rolls down against the next stop, lying in the position of can 11² and having taken 40 the first step in its step-by-step movement through the runway. The second step occurs toward the end of the second half of the first revolution, that is to say, when the runway has been inverted for the second 45 time. The can now occupies the position shown by can 11³. Thus with each complete revolution of the carrier, the runway has been twice inverted, and the can has taken two steps forward, falling with each 50 half turn out of the pocket in which it rests into the opposite, slightly advanced, pocket. A second can is then placed on the loading lip, and at the completion of another revolution, a third can, and so on indefinitely. 55 Coming down on the last half of a revolution, the first can is finally dropped upon the discharge lip 26 of the outer track, and rolls thereon out of the runway and upon the discharge plate 27, on which it rolls out 60 of the housing through the aperture 28 therein. On the completion of the next revolution, the second can emerges. Thus a continuous succession of cans may be passed through the apparatus, each one being repeatedly inverted and subjected to a step- 65

by-step rolling movement which agitates or stirs the contents. Such agitation permits the contents to be quickly and evenly brought to the required temperature, which is then maintained for the rest of the cooking period. Variation in the speed of rotation or in the length of the runways varies the cooking period, but with the factors of heat and speed constant it will be obvious 70 that every can is exposed to the cooking 75 temperature for exactly the same length of time.

Means are provided for feeding a can into the apparatus, with each successive registration of a runway with the charging aperture 29 in the housing, so that each runway may be kept full of cans. A slanting track 31 formed of a pair of channels, open side in, and adapted to receive cans from any suitable source, is aligned with the loading lip 23 when the runway is registered with the loading or charging aperture. Between the channels 31 near the housing is a feed wheel 32 formed with diametrically disposed recesses 33, and rotated in time 80 with the carrier by suitable gearing 34 driven by gear 36 on the same shaft with the worm 14. The wheel 32 picks up the cans, one at a time, and deposits them on the inner end of track 31 from which they 85 roll down onto the loading lip 23 of the runway then in register with the loading aperture. Since the movement of the carrier is continuous, a small amount of clearance is needed longitudinally of the can, to 90 permit complete loading without jamming a can between the carrier and the edge of the loading aperture. A spring pressed lever arm 37 bearing on the can in the wheel, 95 prevents a premature release of the cans from the feed wheel. As shown in Fig. 3, the channel on the leading side of the runways is preferably provided with a lip 38 extending angularly therefrom to direct the can into the runway in case the loading 100 movement occurs a trifle too soon, when the cans are fed by hand.

In Fig. 4 we have shown a modified form of our cooker in which the carrier is made in a plurality of sections which may be operated together as one, in the same manner as that structure already described; or in which one or more sections may be disconnected, leaving one or more sections active. In Fig. 4 two sections are shown, but it 115 will be obvious that any number of carrier sections may be used. The first section nearest the loading aperture is secured to the shaft by keys and is similar in structure to that already described. The second section 120 is rotatable on the shaft and is releasably coupled to the first section, the runways in alignment, by suitable means such as a bolt through apertures 41 in adjacent spokes 6. This is accessible through an aperture in 125 130

the housing, normally closed by a removable cover plate, and when the carrier is turned to the position shown in Figs. 4 and 5. The runway which in this position is the lowest, is attached to the rings 43 by readily removable screws 44, the outer rings 46 being separated at this point, and the adjacent ends respectively connected by the segments 47 to which the removable runway 10 way is attached. Screws 48 fix each segment to the ring ends.

When it is desired to operate only the first section so that the cooking period is correspondingly shortened, the removable runway 15 is detached by reaching up through the opening in the bottom of the housing and removing screws 44 and 48. The cover plate is then removed and the bolt connecting the sections taken out. A cover plate 20 49, shown in Fig. 6 is then applied over the aperture. This plate is provided with a flange 50, adapted to lie between the two sections in a recess in the ring 43, and engaging at its two ends, the shoulders 51 25 formed in the ring, as shown in Fig. 5. It will be seen that with the plate 49 thus positioned and held to the housing by cap screws 52 through the apertures 53 the second section and the third section, if any, 30 attached to it can not move. The flange 50 performs another function. As the cans are carried downwardly on their last half revolution in the first section, they roll into engagement with the smooth face of the 35 flange, instead of being caught and crushed in the open ends of the runways in the second section. When the cans pass the lower end of the flange they roll out of the first section into the space vacated by the removable runway and roll down the removable chute 54, and thus out of the apparatus. Thus without varying the speed of 40 revolution of the carrier, the time of cooking may be varied by disconnecting one or more sections, the cooking period being then determined by the length of the active sections. Thus with a three-section carrier, the third section might be uncoupled from the second and the flange inserted between 45 it and the second section, as already explained. The cans would then travel through the first two sections and discharge from the apparatus at the end of the second section.

If the sections are all active, the cans 55 emerge from the last section and roll down the chute 56 upon the chute 54. Preferably the chute 56 extends closely adjacent the chute 54, and its lower end 57 is hinged or detachable so that it may be turned up 60 or taken off when cans are passing down the chute 54. The structure, otherwise is the same as that first explained.

We claim:

65 1. An apparatus for treating packaged

goods, comprising a runway for said packages, means for inverting the runway, and means stationary relative to the runway and operative by inversion of said runway for causing said packages to progress therethrough.

2. An apparatus for treating packaged goods, comprising a runway for said packages, means for inverting the runway, means stationary relative to the runway and operative by inversion of said runway for causing said packages to progress therethrough, a housing for said runway, and means for heating the interior of said housing.

3. An apparatus for treating packaged goods, comprising a runway for said packages, means for inverting the runway, means stationary relative to the runway and operative by inversion of said runway for causing said packages to progress therethrough, and means for introducing packages into said runway.

4. An apparatus for treating packaged goods, comprising a runway for said packages, means for inverting the runway, means stationary relative to the runway and operative by inversion of said runway for causing said packages to progress therethrough, a housing for said runway, means for heating the interior of said housing, and means for introducing packages into said runway.

5. An apparatus for treating packaged goods, comprising a runway for said packages, means for inverting the runway, means stationary relative to the runway and operative by inversion of said runway for causing said packages to progress therethrough, and means for heating said packages during their progress through said runway.

6. An apparatus for treating packaged goods, comprising a runway for said packages, means for inverting the runway, means stationary relative to the runway and operative by inversion of said runway for causing said packages to progress therethrough, a housing for said runway, means for heating the interior of said housing, and means for introducing a succession of packages into said runway.

7. An apparatus for treating packaged goods, comprising means for passing said packages through said apparatus with a motion including inversion and step-by-step rolling movements.

8. An apparatus for treating packaged goods, comprising a rotatable carrier, longitudinally arranged runways on said carrier for said packages, means stationary relative to said carrier and operative by rotation of said carrier for causing said packages to progress therethrough, a housing for said carrier, and means for heating the interior of said housing.

9. An apparatus for treating packaged goods, comprising a rotatable carrier, longitudinally arranged runways on said carrier for said packages, means stationary relative to said carrier and operative by rotation of said carrier for causing said packages to progress therethrough, and means for introducing a succession of packages into said runways.
10. An apparatus for treating packaged goods, comprising a rotatable carrier, longitudinally arranged runways, on said carrier for said packages, means stationary relative to said carrier and operative by rotation of said carrier for causing said packages to progress therethrough, and means for rotating said carrier.
11. An apparatus for treating packaged goods, comprising a rotatable carrier, longitudinally arranged runways on said carrier for said packages, means stationary relative to said carrier and operative by rotation of said carrier for causing said packages to progress therethrough, means for rotating said carrier, and means for heating said packages during their progress through said runways.
12. An apparatus for treating packaged goods, comprising a rotatable carrier, longitudinally arranged runways on said carrier for said packages, means stationary relative to said carrier and operative by rotation of said carrier for causing said packages to progress therethrough, and means for heating said packages during their progress through said runways.
13. An apparatus for treating packaged goods, comprising a rotatable carrier, longitudinally arranged runways on said carrier for said packages, means stationary relative to said carrier and operative by rotation of said carrier for causing said packages to progress therethrough, a housing for said carrier, means for heating the interior of said housing, and means for introducing a succession of packages into said runways.
14. An apparatus for treating packaged goods, comprising a rotatable carrier, longitudinally arranged runways on said carrier for said packages, means stationary relative to said carrier and operative by rotation of said carrier for causing said packages to progress therethrough, a housing for said carrier, means for heating the interior of said housing, means for introducing a succession of packages into said runways, and means for rotating said carrier.
15. An apparatus for treating packaged goods, comprising a rotatable carrier, longitudinally arranged runways on said carrier for said packages, means stationary relative to said carrier and operative by rotation of said carrier for causing said packages to progress therethrough, means for heating said packages during their progress through
- said runways, and means for introducing a succession of packages into said runways.
16. An apparatus for treating packaged goods, comprising a rotatable carrier, longitudinally arranged runways on said carrier for said packages, means stationary relative to said carrier and operative by rotation of said carrier for causing said packages to progress therethrough, a housing for said carrier provided with charging and discharging apertures with which the ends of said runways are registered during the rotation of said carrier, and means for automatically introducing a package through the charging aperture into each runway during the registration period.
17. An apparatus for treating packaged goods, comprising a rotatable carrier formed in sections each of which is a carrier, longitudinally arranged runways in said carrier for said packages, means in said runways operative by rotation of said carrier for causing said packages to progress therethrough, means for rotating the first section of said carrier and means for releasably coupling the sections together.
18. An apparatus for treating packaged goods, comprising a rotatable carrier formed in sections each of which is a carrier, longitudinally arranged runways in said carrier for said packages, means in said runways operative by rotation of said carrier for causing said packages to progress therethrough, means for rotating the first section of said carrier, and means for releasably coupling the sections together, one runway in each section after the first being removable to permit the discharge of packages from the runways of the preceding sections.
19. An apparatus for treating packaged goods, comprising a rotatable carrier, longitudinally arranged runways in said carrier for said packages, means stationary on said carrier and operative by rotation thereof for causing said packages to progress therethrough.
20. An apparatus for treating packaged goods, comprising a rotatable carrier, longitudinally arranged runways in said carrier for said packages, and tracks having an inclined portion alternated with a stop portion stationary on opposite sides of each runway.
21. An apparatus for treating packaged goods, comprising a rotatable carrier, longitudinally arranged runways in said carrier for said packages, and tracks having an inclined portion alternated with a stop portion disposed on opposite sides of each runway, the stop portions of each track being disposed opposite the beginning of the inclined portions of the companion track.
22. An apparatus for treating packaged goods, comprising an invertible runway for

said packages, and tracks having inclined portions separated by stops stationary on opposite sides of said runway.

23. An apparatus for treating packaged goods, comprising an invertible runway for said packages, and tracks having inclined portions separated by stops disposed on opposite sides of said runway, said stops on each track being disposed opposite the beginning of the inclined portions of the companion track.

24. An apparatus for treating packaged goods, comprising a rotatable carrier formed in a plurality of sections, means for rotating the first section of said carrier, means releasably coupling the sections together, and a guard plate adapted for insertion between a rotating and a non-rotating section.

25. An apparatus for treating packaged goods, comprising a rotatable carrier formed in a plurality of sections, means for rotating the first section of said carrier, means releasably coupling the sections together, a

housing enclosing said carrier, a cover plate 25 closing an aperture in said housing and a flange on said cover plate extending between a rotating and a non-rotating section to prevent the rotation of the latter and the engagement of cans therewith. 30

26. An apparatus for treating packaged goods comprising a runway having on opposite sides thereof tracks, each track comprising inclined portions and stop portions, the inclined and stop portions of each track 35 being staggered in respect of the inclined and stop portions of the opposite track whereby inversion of the runway causes a package to progress therethru.

27. An apparatus for treating packaged 40 goods comprising a runway and staggered pockets disposed on opposite sides of said runway whereby inversion of the runway causes a package to progress therethru.

In testimony whereof, we have hereunto 45 set our hands.

ELMER C. NORTHRUP.
EDWARD H. SPECHT.
